US00D584789S

(12) **United States Design Patent**
Swan

(10) **Patent No.:** **US D584,789 S**
(45) **Date of Patent:** **** Jan. 13, 2009**

(54) **MOUNT**

(76) Inventor: **Richard E. Swan**, 171 West St., E.
Bridgewater, MA (US) 02333

(**) Term: **14 Years**

(21) Appl. No.: **29/298,301**

(22) Filed: **Dec. 3, 2007**

(51) **LOC (9) Cl.** **22-01**

(52) **U.S. Cl.** **D22/110; D22/108**

(58) **Field of Classification Search** **D22/108-110;
42/111-113, 134-140, 142-144, 148**

See application file for complete search history.
